UNITED STATES PATENT OFFICE

WILLIAM NAKAHARA, OF SAN FRANCISCO, CALIFORNIA

DESIGN FOR A COMBINED LAMP BASE AND SWITCH

Application filed September 14, 1929. Serial No. 32,758. Term of patent 7 years.

To all whom it may concern:

Be it known that I, WILLIAM NAKAHARA, a citizen of the United States, and a resident of the city and county of San Francisco and State of California, have invented a new, original, and ornamental Design for a Combined Lamp Base and Switch, of which the following is a specification, reference being had to the accompanying drawing, forming part thereof.

The figure is a perspective view of a combined lamp base and switch showing my new design.

The lamp socket is shown on top of the lamp base and is supported by the base. The bottom of the socket rests upon the head of the statue forming the base, and the axis of the socket coincides with the vertical axis through the base. The back of the figure is plain and of a conventional appearance.

I claim:

The ornamental design for a combined lamp base and switch, as shown and described.

WILLIAM NAKAHARA.
